UNITED STATES PATENT OFFICE.

ROBERT BUCKINGHAM, OF HUNTINGTON, INDIANA.

SHINGLE CUTTER.

Application filed May 12, 1922. Serial No. 560,436.

To all whom it may concern:

Be it known that I, ROBERT BUCKINGHAM, a citizen of the United States, residing at Huntington, in the county of Huntington and State of Indiana, have invented certain new and useful Improvements in Shingle Cutters; and I do hereby declare the following to be a full, clear, and exact description of the invention, such as will enable others skilled in the art to which it appertains to make and use the same.

The present invention relates to sheet cutting devices, and aims to provide a novel and improved machine adapted especially for cutting asphalt and other composition shingles so as to fit the valleys, hips, ridges and gables of building roofs.

It is the object of the invention to provide a cutting device comprising a novel construction and arrangement of parts whereby the shingles can be conveniently and quickly cut, as well as doing the work neatly and cutting the shingles at the desired angle.

Another object is the provision of such a device having a base or body member along which the cutter blade or knife is movable, and provided with novel means for mounting the base or body member on the sheathing of the roof or other boards, and also enabling the device to be held in position by one foot of the operator, whereby the device is conveniently manipulated under different conditions.

A further object is the provision of an arm of novel construction along which the cutter blade or knife is movable hingedly connected to one end of the base or body member in a novel manner for the swinging movement of the arm away from and against the base for the convenient positioning of the shingles, holding thereof during the cutting and removal thereof after being cut, and novel means for positioning the arm when swung against the base.

A still further object is the provision of a novel slide movable along the arm and carrying the cutter blade or knife, which is semi-automatic in operating inasmuch as the slide is restored to initial or starting position when the arm is swung away from the base for the removal of the cut shingle and the insertion of the next shingle to be cut.

Another object is the provision of a novel device for swinging the arm and latching the same to the base.

Another object is the provision of such a

device having a mitre square gage for positioning the shingles to cut them at the desired angle.

With the foregoing and other objects in view, which will be understood as the description proceeds, the invention resides in the construction and arrangement of parts, as hereinafter described and claimed, it being understood that changes can be made within the scope of what is claimed, without departing from the spirit of the invention.

The invention is illustrated in the accompanying drawings, wherein—

Figure 1 is a side elevation of the device as positioned on the sheathing of a roof, showing the arm latched to the base and the slide moved to the position for completing the cut.

Fig. 2 is an opposite side elevation showing the arm raised and the slide returned to initial or starting position.

Fig. 3 is a plan view with the parts as seen in Fig. 1.

Fig. 4 is a longitudinal section of the slide and hinged end of the arm taken on the line 4—4 of Fig. 2 with the arm in position against the base.

Fig. 5 is a cross section on the line 5—5 of Fig. 3.

Fig. 6 is a cross section on the line 6—6 of Fig. 1.

Fig. 7 is a detail view showing the hinged connection between the arm and base, and the stirrup for holding the device down when used in upright position.

Fig. 8 is a perspective view of one end of the base.

The base or body member is elongated and of suitable size, and comprises a bar 11 of wood or other suitable material of rectangular cross-section, with a metal angle member 12 secured over one corner of said bar, and having one flange 13 depending and overlapping one side of the bar, and the other flange 14 disposed on the top of the bar.

In order to conveniently fasten the base on the sheathing of a roof or other similar support, a plate 15 is secured to the lower surface of the base at one end, and is bent to form a hook 16 which can be engaged across and around the edge of a board, as seen in Fig. 1, for holding down such end of the base and preventing the base from being pulled in the direction of the opposite end. A transverse plate 17 is secured to the lower surface of the base at that end

opposite to the plate 15, with its ends projecting from the base and having apertures 18 for fastening said plate down by means of nails, screws, or the like. The device can 5 thus be conveniently fastened down on the roof while shingling, or can be conveniently positioned on any other suitable support, by simply engaging the hook 16 with one edge 10 of the support and fastening the plate 17 down.

The arm 19, along which the slide is movable, has one end hingedly connected to the end portion of the base where the hook plate 15 is located, and one end of the angle member 12 forms the hinge portion of the base. Thus, one end of the flange 13 projects beyond the corresponding end of the bar 11, to provide the projecting portion 20, and the corresponding end of the flange 14 also 15 projects beyond the end of the bar and is bent downwardly and backwardly into a hinge butt portion 21, which is spaced from the portion 20. A hinge pin or rivet 22 extends through the portions 20 and 21, and 20 a spindle or shank 23 has an eye 24 at its lower end embracing the hinge pin 22 between the portions 20 and 21, and one end of the arm 19 is connected to said spindle whereby the arm is capable of turning with 25 the spindle around the hinge pin 22.

The arm 19 is composed of the vertically spaced bars 25 which are secured at one end between the flanges of an end member 26 of the arm, which is of U-shaped section, as seen in Fig. 4. The bend of said end member surrounds the spindle 23, and a filler block 27 is secured between the flanges of said member, to fit the spindle 23 opposite to the bend of said member, whereby 30 the arm is fitted snugly on said spindle with a sliding fit, so that the arm can be adjusted on the spindle to different distances relatively to the base. An adjusting nut 28 is threaded on the upper terminal of the spindle for limiting the upward movement of the arm on the spindle and obtaining the desired adjustment between the arm and base. The opposite ends of the bars 25 are secured between a pair of spaced end members or plates 29, which are located at the free end of the arm, and said plates have the respective tongues or extensions 30 and 31 projecting beyond the lower bar 25 to fit the base. The corresponding end of the 35 base is provided with a longitudinal vertical slot 32 extending from such end, to snugly receive the tongue 31 between the sides of the base, while the tongue 30 is adapted to snugly overlap the flange 13 of the angle member 12, as seen in Fig. 6. This will guide the free end of the arm into proper position on the base, and retain the arm against lateral displacement on the base. The flange 14 is split longitudinally above 40 the slot 32 to accommodate the tongue 31,

and that portion opposite to the flange 13 is bent upwardly to provide an upstanding stop 33 located at one side of the arm 19, to assist in positioning the arm in the base, as well as constituting a stop to limit the movement of the slide as hereinafter pointed out. 70

In order to swing the arm to and from the base, and to latch the arm to the base, a handle 34 is pivoted between ears 35 projecting from the plates 29 at the free end of the arm, and said arm has a hook-shaped latch 36 projecting therefrom to engage the end of the base. The end of the bar 11 has a recess 37 under the flange 14 between the slot 32 and flange 13 for receiving the bill of the hook, and said bill of the hook has a cam surface 38 to engage the end of the flange 14. The handle 34 can be conveniently grasped for swinging the arm, and when the arm is swung adjacent to the base, with the latch 36 in open position, the handle 34 can be swung downwardly, to insert the bill of the hook into the recess 37, thereby moving the cam surface 38 under the flange 14, whereby the free end of the arm is drawn down tightly to clamp the shingle between the arm and base. The cam surface 38 also enables the arm to be clamped down when spaced to different distances from the base, such as when the nut 28 is adjusted for shingles of different thicknesses. 95

The slide 39 which is movable along the arm 19 comprises a bar 40 movable between the bars 25, and opposite side plates 41 and 42 secured to said bar and overlapping the bars 25. The arm thus has a slot or slide-way in which the slide is movable longitudinally of the arm, and the plate 42 has an upstanding handle 43 for conveniently moving the slide. Said plate 42, which may be thicker than the opposite plate 41, has an offset 44 providing a socket for the cutter blade or knife 45, which is adjustable vertically in said socket or offset, and which has the oblique or inclined cutting edge 46 at its lower end. A set screw 47 is carried by the offset or socket portion 44 to clamp the cutter blade in its different adjustments. 100

In order to frictionally retain the slide in initial or starting position, a leaf spring 48 is secured to one side of the slide to overlap and frictionally engage the end member 26 of the arm, as seen in Fig. 4, thereby holding the slide in such position until the slide is manually moved away from such end of the arm. 105

The device can also be used in an upright position with the hinged end down, and, for this purpose, a stirrup 49 has its ends engaging the hinge pin or rivet 22, for receiving one foot of the operator, to hold the device down while the slide is pulled upwardly. In this way, the device can be held down by one foot, with one hand grasping 110

the handle 34 and the other hand grasping the handle 43 to control the arm 19 and slide conveniently.

The mitre square gage includes an angle member 50 having one end overlapping an ear 51 projecting from that side of the base opposite to the flange 13, and said member is pivoted on said ear by means of a pivot bolt 52 having a wing nut 53 under the ear 51 to clamp the member 50 in different angular positions. The ear 51 constitutes a piece of metal secured between the bar 11 and flange 14, as seen in Fig. 5, and the lower flange of the member 50 is flush with or in the same plane as the flange 14, whereby the shingle is supported on said flanges under the arm 19.

In using the device, the gage member 50 is positioned at the proper angle and clamped in place, and the shingle is placed on and against said gage member and base, and when properly positioned, the arm 19 is swung down to clamp the shingle against the base, by moving the latch 36 into engagement with the base and holding the handle 34 down. The slide is then drawn toward the operator, whereby the cutter blade or knife 45 will cut the shingle along the flange 13 which said cutter blade overlaps, as seen in Fig. 5. Then, by swinging the handle 34 to release the latch from the base, the arm is raised to remove the cut shingle and insert the next shingle, and the raising of the arm 19 will cause the slide 39 to slide back to initial position, as seen in Fig. 2, thereby restoring the slide to starting position automatically when the arm 19 is swung to open position. The friction spring 48 of the slide overlaps and frictionally engages the end

member 26 of the arm, to retain the slide in starting position until the slide is again moved for cutting the shingle.

The device can be conveniently used, when shingling, for cutting the shingles off at the desired angle to fit the valleys, hips, ridges and gables of the roof. The cut edges of the shingles are also even and neat, and the work can be done quickly and without the usual annoyance and time involved as compared with the use of ordinary tinner's shears and the like as now done.

Having thus described the invention, what is claimed as new is:

A cutting device comprising a base, a spindle pivoted to the base near one end thereof to swing toward and away from the other end of the base, an arm having means at one end embracing said spindle so that the arm can swing with the spindle toward and away from the base, a cutter slide movable along said arm, a handle pivotally connected with the other end of the arm to swing toward and away from the base and having a hook-shaped latch, the base having means for receiving the bill of the latch when said handle is swung toward the base, said bill having a cam surface to engage the base for clamping the arm against the base with the arm spaced different distances from the base, and portions carried by the arm and base at the last named ends thereof to fit together when the arm is moved adjacent to the base and to prevent the transverse displacement of the arm relatively to the base.

In testimony whereof I have signed my name to this specification.

ROBERT BUCKINGHAM.
